[57] CLAIM

The ornamental design for a terminal block, as shown and described.

DESCRIPTION

FIG. 1 is a top plan view of a terminal block showing my new design;

FIG. 2 is a front elevational view thereof;

FIG. 3 is a bottom plan view thereof;

FIG. 4 is an end elevational view thereof, both ends being identical;

FIG. 5 is a cross-sectional profile view taken along line 5—5 of FIG. 2; and

FIG. 6 is a perspective view thereof.

The block is broken away in FIGS. 1, 2, 3 and 6 to indicate indeterminate length. The connector elements are shown in broken lines for illustrative purposes only.
